Attorneys.

UNITED STATES PATENT OFFICE.

FERNANDO CASABLANCAS, OF SABADELL, SPAIN.

DRAWING APPARATUS FOR TEXTILE ROVINGS.

Application filed July 26, 1920. Serial No. 297,631.

To all whom it may concern:

Be it known that I, FERNANDO CASABLANCAS, manufacturer, subject of the King of Spain, and resident of Sabadell, in the county of Barcelona and Kingdom of Spain, have invented certain new and useful Improvements in Drawing Apparatus for Textile Rovings, of which the following is a specification.

10 My invention relates to improvements in drawing apparatus provided in spinning frames and in other machines of the textile industry devoted to the drawing of textile rovings, and especially to the mechanism used to load the upper cylinders of the pair of drawing cylinders and of the pairs of feeding or intermediate cylinders.

15 To load these cylinders a yoke or bar is generally used that bears upon the central 20 collars of said cylinders, and which, by means of a tie rod, is connected to a lever on the free end of which is suspended a weight. With this usual arrangement, when it is necessary to lift the upper cylinders, 25 the operator must first unload them and to accomplish this he has to walk round the back part of the machine for removing the weight from the end of the lever; and only after doing this may he disconnect the 30 mechanism that transmits the action of this weight to the bar that bears upon the cylinders. This causes a great loss of time and labor, because this operation must be repeated very frequently and has the further 35 disadvantage that to remove the weight it is necessary to pass the hand through the rovings with the risk of breaking the rovings.

40 My invention has for an object to provide a drawing mechanism which allows the upper cylinders to be taken off easily, from the front part of the machine, without making it necessary to disconnect the mechanism that transmits the pressure to these cylinders, and without requiring any operation in the back part of the machine, thus avoiding a great loss of time and labor and the risk of breaking the rovings.

45 My invention consists in providing the yoke or pressure bar that bears upon the cylinders with a handle in its front and upper part and in pivoting the lever with projections thereon at the point where the lever is connected to its fulcrum and to the tie rod.

50 The handle of the pressure bar is at such a

height that in grasping it, the hand will not interfere with the removal of the cylinders.

The accompanying drawing illustrates a transversal section of the drawing mechanism of a spinning frame that embodies my invention.

The invention is shown in the drawing as applied to a drawing mechanism provided with endless belts to convey the roving, but it will be understood that it may be applied exactly in the same way to any system of drawing mechanism.

In the drawings, 1 is the standard that supports the mechanism, 2 and 3 are the feeding cylinders, and 4 and 5 the intermediate cylinders provided with endless belts to convey the roving to the drawing cylinders 6 and 7.

55 In order to load the cylinders 5 and 7 I provide the pressure bar or yoke 8, which has in its forward part a recess 9 that bears upon the gudgeon of the cylinders 7, and is provided at its back part with a projection 10 that bears upon the collar of the cylinder 5.

60 This pressure bar 8 is extended at its forward and upper part to form a hook or handle 11 by which an operator can easily grasp the bar and cause it to swing in order that it may be lifted high enough to remove the cylinder 7 or the cylinder 5. This handle 11 is arranged at a proper height so that the hand that grasps the pressure bar 8 will not interfere with the removal of the cylinders, and at the same time provide sufficient leverage to oscillate with ease the pressure bar 8. When the drawing cylinder 7 is to be removed, the pressure bar 8 is oscillated by the projection 10 swinging upon the gudgeon of the rear cylinder 5, and when the cylinder 5 is to be removed the pressure bar 8 is lifted about the collar of the cylinder 7.

65 The pressure bar 8 is connected at 12 to a tie rod 13 which has formed at its lower end a loop 14 to which is connected a lever 16 provided with a recess 21 to receive same. This lever 16 is fulcrumed at its end 17 to an eye 18 screwed to the angle iron 15 of the frame and at its other end receives the hook 24 from which the weight 23 hangs.

70 The lever 16 is peculiarly constructed in order that it may not become accidentally displaced from its fulcrum, the tie rod 13

- and the weight 25 and hook 24 in the cylinders 5 and 7 being removed. It will be understood that when these two cylinders are removed the pressure plate 8 may slip 5 down thus permitting the lever 16 to fall upon the adjacent parts of the frame. This action is increased by the presence of the weight 25. The end 17 of the lever is downwardly curved and reduced so as to receive 10 a pivot upon the screw eye 18, while projections 19 and 20 extend respectively upwardly and downwardly from the end 17 in order to engage the sides of the eye 18 to prevent accidental displacement of the lever end 15 from the eye when the same is allowed to fall. The projections 19 and 20 are such, however, as not to interfere with the removal of the lever 16 from the fulcrum eye when this is desired.
- 20 The removal of the lever may be accomplished by swinging the same forwardly about the eye in a counterclockwise direction which causes the lower projection 20 to swing through the lower portion of the eye. The loop 14 on the lower end of the tie rod 13 engages about the curved portion of the lever 16 and at the opposite side of this curved portion is a lug 22 extending downwardly from the lever and forming 25 with the downwardly curved end 17 a recess 21 from which the loop 14 may not escape even when the tie rod 13 falls down loosely. The lug 22 is of greater length than the opening of the loop 14 which prevents the loop from sliding along the lever. The free 30 end of the lever 16 is enlarged at the point where the hook 24 engages it so that the free end of the hook may not engage the plate 26 so as to avoid the likelihood of the weight 25 becoming detached from the lever.
- 35 It can be seen therefore that with the use of the present invention the removal of the upper cylinders 5 and 7 is greatly expedited, and furthermore the pressure mechanism is always retained in position to act

in its normal capacity when these cylinders are replaced.

In the drawings the feeding cylinder 3 is shown to be of comparatively great diameter in order to exert a pressure upon the companion cylinder 2; however, it will be understood that a cylinder of smaller size could also be employed and be weighted by proper pressure mechanism, such as, for instance, a part bearing upon the cylinder 55 3 which receives its pressure from the extension piece 10 of the pressure bar 8.

The pressure bar 8 may be arranged as shown in the drawings to provide a circular fitting 28 serving as a guide and support for the cleaning cylinder 29. In the same manner a second fitting might be provided to receive a second cleaning cylinder for the cylinders 3 and 5.

It is obvious that various changes and modifications may be made in the details of construction and design of the above specifically described embodiment of this invention without departing from the spirit thereof, such changes and modifications being restricted only by the scope of the following claim.

I claim:

In a drawing mechanism having upper and lower pairs of drawing cylinders, a pressure bar bearing upon said upper cylinders to fulcrum about either of such cylinders to permit of the removal of the other cylinder, said pressure bar provided with a handle forming at the same time a circular recess serving as a guide and support for a cleaning cylinder; a tie rod pivotally connected to the pressure bar, and weighted means connected to the lower portion of the tie rod and exerting a pressure on the pressure bar.

Signed at Barcelona, in the county of Barcelona and Kingdom of Spain, this 9th day of March A. D. 1920.

FERNANDO CASABLANCAS.
